APPARATUS FOR HANDLING LIQUID SUSPENSIONS

Dan B. Wicker, Dunbar, and Charles W. Cox, St. Albans, W. Va., assignors to American Viscose Corporation, Wilmington, Del., a corporation of Delaware

Application April 4, 1944, Serial No. 529,540

1 Claim. (Cl. 210—196)

1

This invention relates to means for handling liquid suspensions of particulate materials, and more particularly to means for handling liquid suspensions of textile staple fibers.

In withdrawing liquids from suspensions of particulate materials it is a common practice to apply vacuum beneath layers of the suspension distributed on the surface of a so-called vacuum table, the vacuum serving to draw the liquid downwardly from the material at a rapid rate. The vacuum table consists of a horizontally disposed circular table having a liquid-pervious annular deck provided with side walls, and being rotatably mounted above closed chambers which lead separately to the ports of a circular valve through which vacuum is applied or liquid withdrawn.

It is extremely difficult to deposit liquid suspensions of particulate materials on the rotating surface of the vacuum table in the form of a continuous blanket of uniform thickness and density throughout, due to the annular shape of the surface and the consequent difference in linear velocity between the inner and outer portions thereof. However, such uniformity is essential, especially when the particulate material comprises textile fibers, to insure that all of the fibers will be equally treated.

It is, therefore, an object of the present invention to provide a novel means for depositing a liquid suspension of textile staple fibers or the like on the annular liquid-pervious deck of a conventional rotating vacuum table, either in the direction of rotation of the table, or in reverse direction thereto, and, in any case, in the form of a blanket or layer of uniform thickness and density. It is another object of the invention to facilitate the continuous removal of a mass of textile fibers or the like from such a vacuum table after liquid has been withdrawn therefrom.

These and other objects are accomplished by providing a novel trough having a delivery lip or edge such that the material is deposited on each annular subdivision of the deck of the rotating vacuum table in an amount directly proportional to the relative linear velocity thereof.

In the drawings,

Figure 1 is a plan view of a device according to the invention;

Figure 2 is an elevational sectional view of the device shown in Figure 1, one element thereof being shown in diagrammatic form;

Figures 3 to 6 illustrate plan views of modifications of the invention; and

2

Figure 7 illustrates a graphical method of designing an embodiment of the invention.

Referring more particularly to Figures 1 and 2, the numeral 2 indicates a conventional vacuum table having an inner annular periphery 3 defining a central portion 4 and an outer annular periphery 5, and mounted on a spindle or the like (not shown) for rotation in counterclockwise direction above a plurality of closed chambers 10, which lead to a circular valve provided with suitable connections to vacuum lines and discharge receivers (not shown). The inner and outer annular peripheries of table 2 define the limits of a liquid-pervious deck 6 having a blanket or layer 7 of a liquid suspension of textile staple fibers deposited thereon from trough 8 which is inclined at a slight angle with respect to table 2. Pipes 9 positioned above deck 6 are provided with a plurality of spray heads 12, from which the same or different liquids may be applied to the fibrous blanket on deck 6 at predetermined points during rotation of the table, if desired.

An endless belt 13 having spikes or prongs 14 thereon is positioned directly over deck 6 and is driven by pulleys 15 and 16 in the direction indicated by the arrows, so that the spikes or prongs 14 engage blanket 7 and lift it from deck 6 after table 2 has made almost one complete revolution. A doffing roll 17 is provided with flaps 18 which brush the fibers off belt 13 into chute 19 through which they are delivered to container 20. A doffing roll 21 having spikes 22 thereon may also be provided adjacent belt 13, to catch any fibers which may cling to deck 6, or which accidentally pass under belt 13, and to deliver such fibers to a point where they will be engaged by spikes 14 on belt 13 and removed to container 20. Trough 8 for depositing the liquid suspension in uniformly thick layers upon deck 6 of table 2 comprises two side walls 23 and 24 and a plane bottom 25, as shown more clearly in Figure 2, and may be provided with cross-baffles 26 and 27 (Fig. 2) to insure even distribution of the suspension across the entire width of the trough. Trough 8 is provided with a delivery lip or edge 28, the termini of which, regardless of the relative widths of trough 8 and deck 6, substantially coincide with the inner and outer peripheries of the deck, and which, when the trough is projected on the table, substantially defines an arc of a circle, so that when the liquid suspension flows through the trough at a fixed rate and table 2 is rotated at a fixed rate, the portion of the flowing sheet of the liquid suspension which is deposited upon any particular narrow annular subdivision of the

deck is directly proportional to the relative linear velocity of that particular narrow annular subdivision. Thus the amount of the suspension deposited upon the inner portion of the rotating surface is less than the amount deposited on the outer portion thereof, so that the linear velocity differential between such rotating portions is compensated for, the weight of the suspension deposited per unit of annular surface is constant, and the blanket or layer of material laid upon the surface is continuous and of uniform thickness and density throughout.

The projection of the relivery lip or edge 28 of trough 8 on the table may be regarded as defining substantially an arc of an imaginary circle, the locus of the center of which lies at some point on the surface of the deck on a radial line through the center of the table at a right angle to the longitudinal axis of the trough, the distance of such locus from the center of the table being dependent upon the width of the trough, and the width of the particular annular surface to which the trough delivers. The distance of the locus of the center of the circle which defines the trough lip, from the center of the table, may be determined by dividing the difference between the squares of the greater and smaller radii of the table by twice the width of the trough. The greater radius of the table is measured from the center of the table to the annular periphery 5, and the smaller radius is measured from the center of the table to annular periphery 3. From these relationships, the shape of the lip can be determined mathematically.

As seen more particularly in Figures 3 to 7 inclusive, the width of the trough may be the same as that of the annular deck, or it may be greater or less than the latter. In all cases the projection of the termini of the arc forming the lip upon the table substantially coincides with the inner and the outer periphery of the annular surface, and the projected arc is not greater than a semi-circle. Thus, for example, when trough 8 is of the same width as annular deck 6, and is positioned so that its edges are tangential to the peripheries of the deck 6, the locus of the center of the imaginary circle projected from the lip lies on the Y axis at a point midway between the inner and outer peripheries 3 and 5 of deck 6, and the arc is a semicircle, as shown in Figure 3.

In Figure 4, the width of trough 8 is less than the width of annular deck 6, and the trough is spaced away from the X axis and positioned so that neither of its edges is tangential to the peripheries of deck 6. In that case, the locus of the center of the imaginary circle projected from the lip lies on a radial line extending at a right angle to the longitudinal axis of the trough (Y axis) at a point close to the outer periphery of the deck, as shown at 30, and the arc is less than a semi-circle.

In the combination illustrated in Figure 5, the width of trough 8 is greater than the width of deck 6, and the trough is positioned so that one of its edges coincides with the X axis, and the other is tangential to the outer periphery of the deck. There, the locus of the center of the imaginary circle projected from the lip lies on a radial line extending at a right angle to the longitudinal axis of the trough (Y axis) at a point close to the inner periphery of the deck, and the arc is less than a semi-circle.

Figure 6 illustrates a combination in which the width of trough 8 is the same as that of deck 6, but the trough is positioned so that neither of

its edges is tangential to the peripheries of the deck, but one edge thereof coincides with the X-axis. In that instance, the locus of the imaginary circle projected from the lip lies on a radial line extending at a right angle to the longitudinal axis of the trough at a point midway between the inner and outer peripheries of deck 6, but the arc is less than a semi-circle.

For practical purposes and for convenience, it is possible to determine the actual shape of the required lip empirically, by a graphical procedure illustrated by the following discussion:

In order to effectually deposit the material from trough 8 evenly and uniformly upon annular deck 6, any portion of the trough, extending from, and having a width W as measured from, that side of the trough which delivers to the annular portion of annular deck 6 nearest the inner annular periphery 3 of table 2, should deliver to a portion of such deck defined by the inner periphery 3 and an imaginary concentric outer circle having a radius R_t related in accordance with the equation:

$$(R_t^2 - R_o^2) = K W_n$$

where

R_o is the inside radius of the annular deck 6; and

K is a factor which is determined for any given system by the inside and outside radii of deck 6 and the overall channel width of trough 8.

When the width of trough 8 and the inside and outside radii of deck 6 on table 2 are known, the numerical value of K may be found by substituting these known values in the above equation.

Then the annular deck may be divided into a series of annular portions by marking off a series of points each spaced at any arbitrarily selected progressively greater distance from the center of the table and intersecting each of the series of points so marked off with a circle. Then the value of the radius of the outer circle defining each portion is substituted for R_t in the equation, and a value of W is solved for each substitution. Then the trough is divided into parallel, longitudinally extending strips between imaginary lines spaced from that edge of the trough which extends to a point above the inside periphery of the annular surface distances corresponding to the values of W obtained. The intersections of vertical planes through the parallel imaginary lines with the imaginary concentric circles determine loci which define the arc of the trough lip. A scale drawing showing the trough approaching the table at the desired angle may be prepared, showing the trough widths as lines parallel to the sides of the trough, and the deck widths as concentric circles, the intersection of each parallel line with its corresponding circle defining the projection of the delivery lip or edge 28 of each trough width on the table.

As an illustration, let it be assumed that a vacuum table 2 has a diameter of 12 feet, and the central portion thereof has a diameter of 4 feet ($R_o = 2$ feet); while the inside width of trough 8 is 3 feet. In that case, the numerical value of K is 10.67, as determined by substituting the values of 6, 2, and 3 for R_t , R_o , and W respectively in the equation:

$$(R_t^2 - R_o^2) = K W_n$$

Using this value of K , progressively larger widths W of the trough (listed in the table below) can be determined for progressively larger arbitrarily selected annular portions of deck 6.

extending from the inside periphery of the table. These values of R_t and W can then be used in determining circles concentric with the table and lines parallel to the trough sides respectively in a plan view of the table and trough, the intersections of these circles and lines defining the projected arc of the trough lip as shown in Figure 7.

$$R_o = 2; K = 10.67$$

R_t	W
2.5	.21
3.0	.47
3.5	.77
4.0	1.12
4.5	1.52
5.0	1.96
5.5	2.46
6.0	3.00

A mass of textile fibers, such as a mass of artificial staple fibers comprising regenerated cellulose which has been subjected to treatment with water or aqueous media, and which is suspended in such liquid medium, may be continuously deposited from a trough having a specially constructed delivery edge according to our invention, in even and uniform layers upon the liquid-pervious deck of a rotating vacuum table, and when vacuum is applied in the usual manner the liquid is rapidly and efficiently withdrawn downwardly from all of the fibers constituting the mass. If desired the mass of fibers thus uniformly deposited on the deck may be subjected to further treatment thereon, such as, for example, washing to remove residual spinning bath, desulfurizing and removal of desulfurizing agent, bleaching and removal of bleaching agent, or to treatment with appropriate conditioning agents, such as softening agents, lubricating agents, etc., to render the fibers more amenable to further textile processing, such as carding, spinning, etc., which treatments may be carried out in sequence at predetermined segmental intervals of rotation of table 2. Due to the even distribution of the mass of fibers on the annular deck, when vacuum is applied below the deck in the usual manner, the treating liquid which has been sprayed or showered upon the fibers is drawn downwardly through the mass at a rapid and uniform rate and penetrates all of the fibers equally, with the result that fibers having uniform properties are obtained. After the liquid has been withdrawn, the blanket or layer of fibers may be continuously removed from the table and sent to a suitable container or the like, as previously described herein.

Although the invention has been shown and described with more particular reference to use thereof in connection with liquid suspensions of textile staple fibers, it will be apparent that the

novel trough may be used whenever it is desired to deposit even, uniform layers of liquid suspensions of particulate material on a rotating annular surface for any purpose.

5 We claim:

In an apparatus which comprises a rotating foraminous annular surface disposed in a horizontal plane and a trough inclined from the vertical for depositing a liquid suspension of particulate material thereupon so that the amount of suspension deposited on any given unit width of the annular surface is directly proportional to the relative linear velocity of such unit, said trough having a delivery edge the projection of which on the annular surface effectively defines substantially an arc of a circle and the locus of the center of which circle lies on the annular surface on a radial line through the center of said surface extending at a right angle to the longitudinal axis of the trough, and the termini of which arc coincide with the inner and outer peripheries of the annular surface, the locus of points on said arc being ascertainable from the equation

$$(R_t^2 - R_o^2) = K W$$

(where R_o is the inside radius of the annular surface and K is a factor determinable by substituting in the equation the outside radius of the annular surface for R_t and the width of the trough for W) by dividing the width of the annular surface into a number of portions between imaginary concentric circles and substituting the value of the radius of the outer circle defining each portion for R_t in said equation, solving for W , and dividing the trough into parallel, longitudinally extending strips between imaginary lines spaced from that edge of the trough which extends to a point above the inside periphery of the annular surface distances corresponding to the values of W obtained, the intersections between the imaginary concentric circles and vertical planes through said parallel imaginary lines constituting the loci defining the arc.
